TRAY

Walter R. Roycroft, Ozone Park, N. Y., assignor
to Western Electric Company, Incorporated,
New York, N. Y., a corporation of New York

Application February 5, 1938, Serial No. 188,831

6 Claims. (Cl. 211—126)

This invention relates to trays and more particularly to multiple trays.

In the manual assembly of different types of apparatus the groups of parts for each apparatus usually require compartments varying in size, number and arrangement.

An object of the invention is to provide a multiple tray with a variable arrangement of compartments.

With this and other objects in view, the invention contemplates like body members, locking means for securing a selected number of body members together in general alignment, like side members arranged to be secured to the ends of the assembled body members and different types of partitions with which trays having one or more sections may be provided with a varied arrangement of compartments.

Other objects and advantages will be apparent from the following detailed description taken in conjunction with the accompanying drawing, wherein

Fig. 1 is a perspective view of one form of assembly illustrating the invention;

Fig. 2 is an exploded perspective view of one tray section illustrating two forms of partitions;

Fig. 3 is a perspective view of another partition;

Fig. 4 is a perspective view illustrating one of the locking means between the side member and a body member, and

Fig. 5 is an enlarged perspective view of the locking means between the body members.

Referring now to the drawing, numeral 10 designates side members which are identical in construction having vertically extending leg portions 11 merging into outwardly flared upper portions 12, the latter portions serving to close the ends of body members 13 in assembling. The body members are substantially U-shaped in general contour having side walls 14 which flare outwardly to conform to the outer edges of the portions 12 of the side members. In the bottom portion of the body members 13 are longitudinally extending elongated apertures 16 disposed in selected positions as shown in Figs. 1 and 2 and transversely extending elongated apertures 17. Similar apertures 18 are formed in the side walls 14 of the body members. In one of the outer edges of the side walls 14 are formed cut-away portions or recesses 20 positioned in general alignment with the elongated apertures 16 and in the same edge of the bottom portion of the body members similar recesses 21 are formed, the latter being in general alignment with the

apertures 17. The purpose of these apertures and recesses is to receive integral lugs shown on the partitions illustrated in Figs. 2 and 3.

One form of partition is of substantially inverted V-shape and indicated by numeral 24. This partition has downwardly projecting integral lugs 25 receivable in the apertures 16 of any one or all of the body members 13 for dividing each body member, in which it is disposed, into two longitudinally extending compartments with inner walls which flare outwardly as illustrated in Fig. 1. Elongated apertures 26 are formed in the partition 24 adjacent the vertical center line of each wall and in general alignment with the elongated apertures 18 of the body member in which it is disposed.

Another form of partition is illustrated at 30 which may be used in cooperation with the partition 24 for dividing one of the body members or tray sections into three or four compartments. The partition 30 has integral lugs 31 receivable in the apertures 18 and 26 and an integral lug 32 receivable in one of the apertures 17. As shown in Fig. 2 the partitions 30 are identical in construction and may be inserted in place on either side of the partition 24.

The other partition shown in Fig. 3 is for separating the body members or tray sections into two laterally extending compartments and/or for separating one tray section from another. This partition, indicated at 35, extends the full width of the body member having outwardly extending end edges conforming to the side walls 14 with lugs 36 integral therewith and receivable in the apertures 18 while the lower edge of the partition has integral lugs 37 projecting downwardly and receivable in the apertures 17. When this partition 35 is used to separate the tray sections composed of two or more body members, the partition is positioned so that the lugs 36 will enter the recesses 20 and the lugs 37 will enter apertures formed by the recesses 21. The adjacent side edge of an adjoining body member associated with the recesses 21 complete apertures for the lugs 37.

Disposed at spaced positions near the side edges of each body member are latch or wedge receiving loops 40 which may be formed of separate pieces of material and secured to the body members but in the present illustration are pierced from the body members to form loops for receiving wedge shaped latches. The various portions of the tray, i. e. the end members, the body members and partitions are formed of sheet material, preferably sheet metal of a suit-

able gauge to render them somewhat flexible so that the different parts may be readily assembled yet when assembled would form a somewhat rigid structure. For securing the body members together, they may be positioned end to end, thus aligning the retaining loops 40 in adjacent pairs and in these pairs of retaining loops, as illustrated in Fig. 5, wedge shaped latches 42 may be inserted. The outer edges of the latches 42 remain parallel with respect to each other whereas the tapered inner edges bring about a locking relation between the loops 40 and the latches 42 as the latches are forced into locking positions.

A similar locking means is employed for securing the end members 18 to their respective body member with the exception that wedge shaped latches 45 are stamped out of and bent at right angles to the end members and positioned to be received in the loops 40 of the bottom portion of the adjacent body members. Wedge shaped latches 46 similar to those shown at 42, but shorter in length, are used in cooperation with the latches 45. Another latching means is illustrated in Fig. 4 and has a latch element 47 with a tapered upper surface. This element is bent into a right angle so that the smaller end will extend around the edge of the side member while the larger portion extends through the adjacent loop 40. A cooperating straight latch element 48 with a tapered lower surface may be driven in place from the left side (Fig. 4) and in so doing the element 47 will be urged to the right to force the side member into intimate engagement with the body member.

With a group of side members, body members and partitions, either a tray with a single section or a tray with several sections may be formed and each section may be formed with a single compartment or a plurality of compartments, as illustrated in Fig. 1. If a multiple tray, as illustrated in Fig. 1, is desired, the body members are secured together by the latches 42 being forced in place. The side members are next secured to the ends of the assembled body members by the aid of the latches 45-46 and 47-48. The desired partitions may be inserted in place; for example the partitions 24 and 30 may be inserted in the first body member or tray section. To insert the partitions 30, after the partition 24 has been inserted in place, the walls 14 may be flexed outwardly to allow the lugs 31 to pass downwardly until they enter the apertures 18 and 26. In a similar manner the desired number of partitions 35 may be inserted in places illustrated in Fig. 1. If it is desirable to add other tray sections to those already formed, additional body members with a selected arrangement of partitions may, in a similar manner, be secured to either end of the multiple tray sections already formed. After such a tray has been assembled, it may be revised at any time by removing and rearranging the partition or by removing any of the latches 42, 45, 46, 47 or 48 and body portions may be removed or others added, if desired. If more than one multiple tray is desired they may be disposed in stacked formation, as illustrated in Fig. 2, the side members being placed one upon another and secured in place by latches 42 inserted in the adjacent sets of retaining loops 48 pierced in the end members 18 adjacent their upper and lower edges.

The embodiment of the invention herein dis-

closed is illustrative only and may be widely departed from in many ways without departing from the spirit and scope of the invention as pointed out in and limited solely by the appended claims.

What is claimed is:

1. In a tray, a selected number of body members having apertures therein, and like partitions having projections receivable in the apertures for securing one of the partitions at the juncture of the members for separating them into tray sections and for securing one of the partitions in a selected member to form compartments therein and means to secure the body members together.
- 10 2. In a tray, a tray member substantially U-shaped in cross section having a latch receiving element adjacent the edge thereof, a side member positioned to close the end of the tray member, a latch element having a substantially right angle contour with one portion disposed adjacent the side member and the other portion disposed in the latch receiving element, and a latch member cooperating with the right angle element for forcing the side member into intimate engagement with the tray member when the latch member is driven into place.
- 15 3. In a tray, substantially U-shaped tray sections having apertures therein and recesses in edges thereof, like partitions having projections receivable in the apertures and the recesses to separate the tray sections one from another and divide the tray sections into compartments, an edge of one tray section closing the recesses of another to hold the projections therein, and means to secure the tray sections together.
- 20 4. In a tray, a tray member having a retaining loop disposed adjacent the end thereof, a side member positioned to close the end having an aperture therein disposed in general alignment with the retaining loop and a wedge-shaped latch member disposed adjacent the aperture and receivable in the retaining loop, and a removable latch member receivable in the aperture and retaining loop and cooperating with the first mentioned latch member to move the side member into intimate engagement with the tray member and secure the tray member and side member together.
- 25 5. A tray comprising like substantially U-shaped body members formed at ends thereof and intermediate the ends thereof for interconnection with portions of partitions, means to secure the body members together in abutting end to end engagement with each other, and partitions similar in contour to the ends of the body members and formed for interconnection with the body members between their ends and at the juncture of the ends thereof.
- 30 6. In a tray, a selected number of substantially U-shaped body members formed at ends thereof and intermediate the ends thereof for interconnection with portions of partitions, means to connect the body members together end to end, and like partitions having portions for interconnection with the body members between their ends and at the juncture of their ends for separating the members from each other into tray sections and separating the members into compartments.
- 35 7. WALTER R. ROYCROFT.
